United States Patent Office.

FRANCIS M. HOWARD AND DANIEL W. AVERY, OF ST. PAUL, INDIANA.

Letters Patent No. 77,487, dated May 5, 1868.

IMPROVED DITCHING AND GRADING-MACHINE.

The Schedule referred to in these Letters Patent and making part of the same.

TO ALL WHOM IT MAY CONCERN:

Be it known that we, FRANCIS M. HOWARD and DANIEL W. AVERY, of St. Paul, in the county of Decatur, and State of Indiana, have invented a new and improved Ditching-Machine; and we do hereby declare that the following is a full, clear, and exact description thereof, which will enable others skilled in the art to make and use the same, reference being had to the accompanying drawings, forming part of this specification.

This invention relates to a new and improved method of constructing machines for ditching, and for excavating dirt, whereby the same are more simple in construction, more effective in operation, not liable to get clogged or out of repair, and which can easily be adjusted for the plough to run at any desired depth. It consists in the construction of the plough, and the combination of the same with the elevator-beam and the slotted side-irons of the plough. It consists, also, of an endless-carrier belt, to which are attached metal jaws, passing over and driven by toothed wheels, in combination with the ground or driving-wheels of the machine, by means of which, said ground-wheels communicating motion through a spur-gear wheel and spur-gear pinion to said toothed wheels, said endless-carrier belt is driven, so that the dirt loosened by the plough is carried by said belt over the rear end of the machine. In the accompanying plate of drawings—

Figure 1 is a side view of our invention, a portion of the frame being removed to show the construction.

Figure 2 is a plan view of the same.

Figure 3 is a detail view of the under side of the endless belt.

Figure 4 is a detail cross-section of the same, showing the manner of securing the carrier-jaws to the belt. a^1 is the frame of the machine. b is the elevator or carrier-beam. d are the ground-wheels. e' is a spur-gear wheel on shaft A . A is the main shaft. f is a spur-gear pinion on shaft G . g^2 are toothed wheels on shaft G , by means of which motion is communicated to the endless-carrier belt B . B is the endless-carrier belt. a are metallic jaws on belt B . a^2 are rivets securing jaws a to belt B . m are the slotted side-irons of the plough. D is a rod passing through the frame a^1 and the slots in the side-irons m . n are nuts on rod D , on the inside of the frame a^1 to hold the side irons m to the frame a^1 . n' are nuts on the said rod D , on the outside of the frame a^1 , to hold said rod D in the frame a^1 . e is the plough. d' is an attachment to frame a^1 , by means of which the machine is drawn. H are uprights or supports to support shaft G . g^1 are metallic plates, by means of which the carrier-beam b is pivoted to the shaft G .

The frame a^1 is composed of two parallel beams, secured together by suitable end-pieces, of such length and of such distance apart as to receive the carrier-beam b , and allow the same to move freely between the beams and end-pieces of the frame a^1 , as shown in the drawing.

To the under side of the beams of the frame a^1 , and near to the rear end of the same, and rotating in suitable boxes attached thereto, is an iron shaft or axle, A . Said axle A extends across from one of said beams to the other, and beyond the same, as shown in the drawing, so as to receive the wheels d , said wheels d being keyed to the ends of said axle A in the ordinary way. Said wheels d may be made of cast iron or other suitable material, and of any convenient diameter. We prefer them about the diameter of thirty-two inches. Said wheels d are provided upon their circumference with teeth or cogs, which prevent the said wheels from slipping on the ground. Upon the said axle or shaft A , and between one of the wheels d and the frame a^1 , and nearer to said frame a^1 , is keyed a spur-gear wheel,

Upon the upper sides or edges of the beams of the frame a^1 , and nearly over the axle A , and rigidly secured to said frame a^1 , are two uprights or supports H , provided with suitable bearings to support the shaft G , in which said bearings said shaft G rotates. Upon each end of the shaft G , and between the bearings of the same, and so as to be seven inches apart, or thereabouts, are two metallic plates g^1 , between which is secured one end of the elevator or carrier-beam b , in such a manner as that carrier-beam b will turn upon the shaft G as upon a pivot.

Between and near to said plate g^1 , and keyed upon the axle G , are two toothed wheels g^2 , which, by the teeth or spurs in the circumference thereof, engaging with the ribs of the metallic jaws a of the belt B , carry the said belt B around with said toothed wheels g^2 .

The other or front end of the elevator or carrier-beam *b* is pivoted to a roller, *R*, which said roller *R* is also pivoted to the slotted side-irons *m*, so that the front end of the elevator or carrier-beam *b* may be raised or depressed.

The elevator or carrier-beam *b* may be of any convenient length, but we have found that when made of the length of about nine feet they are most convenient.

The side-irons *m* are made of metal, and are arcs of a circle, of about the diameter of eighteen feet, corresponding with the arc described by the forward end of the carrier-beam *b*, to which said side-irons are pivoted. This construction causes the plough *e*, attached to said side-irons *m*, to have the same inclination when working in a deep ditch as when working in a shallow one. Said side-irons *m* are provided with a slot through nearly the entire length of the same, above the roller *R*, to receive the rod *D*, upon which said side-irons *m* move when the elevator or carrier-beam *b* is being elevated or depressed; said rod *D* being provided with nuts, *n*, which, by being turned upon screw-threads upon said rod, hold the said elevator or carrier-beam *b* at any required elevation, there being one of said side-irons *m* pivoted to each side of the said elevator or carrier-beam *b*. Below the roller *R* the said side-irons *m* are bent forward, and upon the same is firmly secured the plough *e*.

The plough *e* is made of any convenient form, as of a metallic plate, sharpened out on the forward edge, and curving upward and backward, so as to reach the top of the roller *R*, as shown, and is secured to the side-irons *m* in such a way as that the same may be easily removed at any time, and another plough substitute its place. The roller *R* turns upon the same pivot which secures the side-irons *m* to the elevator or carrier-beam *b*, and may be of any convenient size to guide the endless belt *B*, so as that the same will pass, in the motion of the same backward, near to the upper and back edge of the plough *e*, so that the dirt loosened by the plough *e* will be carried backward by said endless belt *B*.

The endless-carrier belt *B* is made of leather or other suitable material, of about the width of seven inches, having across the same the metallic jaws *a*, riveted to said belt by the rivets *a*², as shown, sufficient space being allowed between said jaws *a* to receive the teeth of the wheels *g*², and so as to form an endless flexible trough, of about three inches deep and seven inches wide.

To the front end of the frame *a*¹ is any convenient metallic attachment, *d*², to receive a chain, by means of which the machine is drawn. To the front end of the frame *a*¹ may also be secured any convenient apparatus for raising and lowering the forward end of the elevator or carrier-beam *a*¹ as a rack and pinion, whereby the plough may be adjusted to ditches of differing depths.

The spur-gear wheel *e*¹ and pinion *f* and the wheels *g*² are constructed with respect to size and the number of teeth contained in each respectively, so as that the motion of the belt *B* will be faster than the forward motion of the machine, in the proportion of nine to one, whereby the dirt loosened by the plough *e* will be very rapidly carried backward and discharged, so as not to clog or hinder the machine.

The operation is readily seen from the drawing.

Constructed as above described, it constitutes a durable ditcher or excavator, the advantages of which are that the same is not likely to get out of repair, and which is not likely to clog, and which may be easily adjusted to ditches of differing depths.

We claim as new, and desire to secure by Letters Patent—

1. The adjustable slotted guides *m*, in combination with the plough or cutter *e*, substantially as and for the purposes set forth.
2. In combination with the above, and with the toothed wheel *g*¹ and shaft *G*, we claim the jaws *a*, riveted to the belt *B* and the pivoted carrier-beam *b*, all constructed, arranged, and operating as and for the purposes set forth.

The above specification of our invention signed by us, this   day of   , 1867.

FRANCIS M. HOWARD,
DANIEL W. AVERY.
